(57) **CLAIM**

The ornamental design for a fabric care appliance, as shown and described.

DESCRIPTION

FIG. 1 is a perspective view of a fabric care appliance according to our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top plan view thereof with the portion of the article above the line 8-8 in FIG. 4 removed.

The broken line showing of various features is for the purpose of illustrating portions of the fabric care appliance that form no part of the claimed design.

Dash-dot lines adjacent un-shaded areas represent bounds of the claimed design and form no part of the claimed design. Diagonal shading indicates transparency.
